ABSTRACT OF THE DISCLOSURE

A ventilating curtain made of flame-resistant fabric that includes a body portion connected to an apertured header portion. The header portion being formed by a plurality of intersecting sets of strips that are interconnected to form a lattice to insure the free flow of air therethrough.

BACKGROUND OF THE INVENTION

Field of the invention

This invention relates generally to a ventilating curtain and more particularly to a hospital cubicle ventilating curtain that is suspended from the ceiling to ensure privacy.

Description of the prior art

Most hospital rooms are provided with two or more beds so that patients can share room facilities and thus reduce the cost and expense of medical services when a person's illness requires him to become a patient in a hospital.

When rooms are shared by two or more patients, it is customary to provide a sliding curtain that is hung from frames suspended from the ceiling to form a cubicle around each bed and thus insure privacy when needed. The curtain is usually constructed having a body portion and a top header portion, with the header portion being formed of nylon having an eye mesh or square mesh weave to ensure the flow of air therethrough. It has been found, however, that the ventilating characteristic of the aforesaid header portion is considerably reduced as a result of air-borne cotton lint that is normally attracted to said header portion by the static electricity present in nylon.

The present invention eliminates the above problem by providing a header portion having a lattice type of construction to ensure the free flow of air therethrough, and thus provide a better ventilating curtain.

SUMMARY OF THE INVENTION

The ventilating curtain of the present invention includes a body portion and a header portion both made of flame-resistant fabric to protect the patient against the accidental starting of fires. The header portion has a plurality of openings therein being separated from each other by vertically and horizontally extending sets of intersecting strips that are interconnected to form a lattice. One end of the vertically extending strips is secured to the top edge of the body portion and the other end of said vertically extending strips is secured to the top-most horizontally extending strip. A binding portion is then secured to the respective side edges of the body portion and to the edges of the horizontally extending strips to form side bindings for the entire curtain. Eyelet means are further provided in the top-most horizontally extending strip to permit the curtain to be slidably affixed to a supporting structure which thus forms a cubicle around a hospital bed to insure privacy when needed. The lattice type of construction permits the free flow of air therethrough and provides better ventilation than the eye mesh and/or square mesh nylon type header, which as previ-

2

ously noted, becomes easily covered with cotton lint or dust and prevents the free circulation of air.

Accordingly, an object of the present invention is to provide a ventilating curtain that permits the free flow of air therethrough.

Another object and feature of the present invention is to provide a ventilating curtain that can be used in a hospital to form a cubicle around a patient's bed to ensure privacy.

A further object and feature of the present invention is to provide a hospital cubicle curtain that is economical to manufacture and gives long lasting service.

The above and other objects, features and advantages of the present invention will become more apparent from a consideration of the following detailed description when taken in conjunction with the accompanying drawings.

BRIEF DESCRIPTION OF THE DRAWINGS

FIG. 1 is a front elevational view of the ventilating curtain constructed according to the present invention;

FIG. 2 is a sectional view taken through line 2—2 of FIG. 1;

FIG. 3 is a sectional view taken through line 3—3 of FIG. 1;

FIG. 4 is a sectional view taken through line 4—4 of FIG. 1;

FIG. 5 is a sectional view taken through line 5—5 of FIG. 1; and

FIG. 6 is a sectional view taken through line 6—6 of FIG. 1.

DESCRIPTION OF THE PREFERRED EMBODIMENT

Referring to the drawings, numeral 10 represents a hospital cubicle curtain, preferably made of opaque fabric that is treated to retain fire-retardant qualities to provide maximum safety for hospital rooms. The curtain is provided with a body portion 12 and a header portion 14 which are connected to one another in a manner hereinafter described.

The body portion 12 is preferably constructed of one piece of fabric, thus having no vertical seams. The bottom edge 16 of said body portion 12 is turned over to form a bottom hem 18 and is closed by means of stitching 20. The top edge 22 of said body portion 12 is turned over and inturned, as shown in FIG. 3, to form a 3-ply top hem 24. The top hem 24 serves to connect the body portion 12 of curtain 10, to the header portion 14.

The header portion 14 is constructed of vertically and horizontally extending sets of intersecting strips, 26 and 28 respectively, interconnected to form a lattice. In the preferred embodiment, each of said strips 26 and 28 is formed of two superimposed pieces of fabric having in-turned facing side edge portions 30 and 32 secured together by means of stitching 34. The arrangement is such that the horizontally extending strips 28 are closed completely over the vertically extending strips 26 as shown in FIG. 2, to prevent lint or other bacteria carriers from collecting inside said strips.

Referring to FIG. 4, one end 36 of the vertically extending strips 26 is inserted within the top hem 24 of body portion 12, with said top hem then being closed by means of stitching 38. Each of the vertically extending strips is then turned upward and further secured to the top hem 24 by means of bar tack 40. The other end 42 of said vertically extending strips 26 is inserted between the two superimposed pieces of fabric constituting the top-most horizontally extending strip, with said top-most horizontally extending strip then being closed by means of stitching 44, as shown in FIG. 5. The top-most horizontally extending strip thus becomes, in effect, the top binding portion of curtain 10.

Curtain 10 is further provided with side binding portions 46, each having first and second portions 48 and 50, respectively. The side binding portions 46 are formed of flame-resistant fabric with the first portions 48, folded over the respective side edges of body portion 12 and the second portions 50 folded over the ends of the horizontally extending strips 28. The side edges of binding portions 46 are then turned inwardly, as shown in FIG. 6, and closed by means of stitching 52. The ends of the binding portions 46 are also closed by means of a triangular shaped row of stitches 54.

The curtain is further provided with a plurality of spaced eyelets 56 located at the juncture of the vertically extending strips 26 and the top-most horizontally extending strip 28. Additional eyelets are also provided at the juncture of the side binding portions 46 and the ends of the top-most horizontal strip 28. The eyelets 56 are reinforced by means of stitching 58 and serve to slidably affix the curtain to a supporting structure by means of conventional hooks.

There are no pleats, twists, rolls or raw edges in any of the parts of the above curtain and the fabric thereof can be dyed in decorative colors.

While a specific embodiment of the invention has been shown and described in detail, it will be readily understood and appreciated that various changes or modifications thereof may be made without departing from the spirit and scope of the invention as set forth in the appended claims. For example, the lattice construction could be such that the vertically extending strips close completely over the horizontally extending strips. In this event, the end edges of the vertically extending strips that close over the top-most horizontal strip should be turned inwardly and closed by stitching to eliminate the presence of any raw edges.

I claim:

1. A ventilating curtain for use with a supporting structure, said curtain comprising in combination:
  - (a) a body portion and a header portion;
  - (b) said body portion being formed of fabric having turned over hem portions at the top and bottom edges thereof;
  - (c) said header portion having a plurality of openings

therein being defined by vertically and horizontally sets of intersecting strips of fabric interconnected to form a lattice;

(d) means for fixedly securing together said interconnected strips at the respective intersecting junctures thereof;

(e) means for fixedly securing one end of the vertically extending strips within the top hem portion of said body portion, and means for fixedly securing the other end of said vertically extending strips to the top-most horizontally extending strip;

(f) a binding portion comprising strips of fabric having a first portion fixedly secured to the respective side edges of said body portion and a second portion projecting above the top edge of said body portion;

(g) means for fixedly securing the second portion of said binding portion to the end edges of said horizontally extending strips; and

(h) means for slidably affixing said curtain to said supporting structure.

2. The ventilating curtain as recited in claim 1, wherein the means for slidably affixing said curtain to said supporting structure includes a plurality of spaced eyelets in the top-most horizontally extending strip and located at the juncture of said vertically extending strips and the top-most horizontally extending strip.

3. The ventilating curtain as recited in claim 1, wherein the means for slidably affixing said curtain to said supporting structure includes an eyelet in the second portion of said binding portion and located at the juncture of said second binding portion and the end edges of said top-most horizontal strip.
